Hugh J. MacCotter, P.O. Box 2, Jacksonville
Beach, Fla. 32050

Filed Sept. 18, 1968, Ser. No. 13,603

Term of patent 14 years

Int. Cl. D10—11

U.S. Cl. D52—6

FIG. 1 is a side elevational view of a pipe locator device showing my new design;

FIG. 2 is a top view thereof;

FIG. 3 is a bottom view thereof;

FIG. 4 is a front elevational view thereof with the telescoping member extended for use thereof; and

FIG. 5 is a top view thereof with the telescoping member extended for use thereof.

The essential features of the design are shown in full lines; and in FIGS. 1, 2 and 3 the telescoping member is shown in its retracted condition.

I claim:

The ornamental design for a pipe locator device, substantially as shown and described.
